WRIST WATCH CASE LUG

William H. Maxwell, Elberton, Ga.

Application December 24, 1943, Serial No. 515,629

1 Claim. (Cl. 24—265)

This invention relates to new and useful improvements in wrist watches and more particularly to a wrist watch strap retaining lug, the principal object being to provide a lug of a certain length to cover the greatest length necessary for such a device and to so form the device as to permit the same to be sheared off to the desired length in an easy and convenient manner preparatory to installation.

Other objects and advantages of the invention will become apparent to the reader of the following description.

In the drawing—

Figure 1 represents a fragmentary detailed sectional view showing the lug in use.

Figure 2 is a longitudinal sectional view of a lug and barrel apart from its use with a watch case.

Figure 3 is a side elevational view of the lug. Referring to the drawing wherein like numerals designate like parts, it can be seen that numeral 5 denotes a wrist watch case having arms 6 projecting from the ends thereof. Numeral 7 denotes a wrist watch band which has a loop 8 at one end thereof for disposition over holding means generally referred to by numeral 9. The holding means 9 customarily consists of a barrel 10 having a pin 11 projecting from one end and containing a spring 12 urging a lug through the other end of the barrel and into a recess or opening in the corresponding arm 6 of the watch case 5.

However, in carrying out the present invention a special form of lug is employed and this lug is generally referred to by numeral 13.

The improved lug consists of a cylindrical body 14 slidably disposed in the barrel 10 and having a reduced portion 15 which slides through the opening in the adjacent end of the barrel 10. 5 From the reduced portion 15 projects an elongated pin 16 having at regularly spaced intervals collars 17. The pin 16 is made of a material which can be easily snapped or sheared off and this is done immediately under any one of the collars 17 in order to cut the lugs down to the desired size for use in conjunction with a watch of a specific width.

While the foregoing specification sets forth the invention in specific terms, it is to be understood that numerous changes in the shape, size and materials may be resorted to without departing from the spirit and scope of the invention as claimed hereinafter.

Having described the invention, what is 20 claimed as new is:

A wrist watch strap holder comprising a barrel, a spring in the barrel, a lug extending through one end of the barrel and urged outwardly by the spring for projection into an apertured arm on 25 the watch, said lug consisting of a portion slidably in the barrel and a pin projecting from the slide portion and externally of the barrel and adapted to be easily sheared off at any one of a plurality of definitely spaced intervals, said pin 30 being provided with stop collars at said intervals for limiting play of the pin in said arm under the urge of the spring.

WILLIAM H. MAXWELL.
